US00D575499S

(12) **United States Design Patent**
Seamans

(10) **Patent No.:** **US D575,499 S**
(45) **Date of Patent:** **** Aug. 26, 2008**

(54) **FOOTWEAR**

(75) Inventor: **Scott Seamans**, Boulder, CO (US)

4,888,887 A 12/1989 Solow
4,967,750 A 11/1990 Cherniak
D345,245 S 3/1994 McDonald

(73) Assignee: **Crocs, Inc.**, Niwot, CO (US)

(**) Term: **14 Years**

(21) Appl. No.: **29/244,661**

(Continued)

(22) Filed: **Dec. 8, 2005**

(74) Attorney, Agent, or Firm—Faegre & Benson, LLP

(57) **CLAIM**

The ornamental design for footwear, as shown and described.

DESCRIPTION

FIG. 1 is a front perspective view.

FIG. 2 is a front view.

FIG. 3 is a back view.

FIG. 4 is an inner side view.

FIG. 5 is an outer side view.

FIG. 6 is a top view; and,

FIG. 7 is a bottom view.

The broken line showing of the sole, strap, upper, and surface treatment thereof is for illustrative purpose only and forms no part of the claimed design.

1 Claim, 7 Drawing Sheets
